UNITED STATES PATENT OFFICE.

ERNEST H. STRAUSS, OF CHICAGO, ILLINOIS.

LAMP-SHADE AND LIGHT-DIFFUSER.

1,329,147.

Specification of Letters Patent.

Patented Jan. 27, 1920.

Application filed June 18, 1917. Serial No. 175,473.

To all whom it may concern:

Be it known that I, ERNEST H. STRAUSS, a citizen of the United States, residing at Chicago, in the county of Cook and State 5 of Illinois, have invented a certain new and useful Improvement in Lamp-Shades and Light-Diffusers, of which the following is a specification.

My invention relates to lamps generally, 10 but particularly to lamps in the case of which it is sometimes necessary to look at or in the direction of the source of the light, and has for its object the production of a shade and diffuser which will give the maximum light in any given direction or directions, with little or no glare to the eyes upon looking at or in the direction of the source of the light.

I attain these objects by a shade and diffuser illustrated in the accompanying drawings, in which Figure 1 is an elevation of a typical segment; Fig. 2 of a segment with one end closed; Fig. 3 a cross section of the same showing three types (a, b and c) of 25 corrugation of the diffuser proper; Fig. 4 shows the device mounted on a bracket and suspended so as to serve a desk or work bench; Fig. 5 shows a mounting of the device on a standard; Figs. 6 and 7 show segments of the faces of the corrugations shown in cross section in Fig. 3. Figs. 8 and 9 show the faces of possible assemblings and mountings of the diffuser; Fig. 10 is an elevation of the mounting shown in Fig. 9; 30 Fig. 11 shows in simple form how the diffuser may be built into the walls of a room, and Figs. 12 and 13 show the device in possible forms of chandeliers. The same reference characters refer to the same, similar 40 or corresponding parts throughout the various views.

The device consists of a diffuser proper, a reflector, and, in certain forms, a shade. The diffuser proper is made of glass with 45 longitudinal corrugations having those sides of the crests on which light rays fall directly from the source or sources of the light, frosted, so as to diffuse them, but having the other sides, or those upon which in- 50 direct or reflected rays fall, clear or transparent, so as to permit their passage with little or no absorption; while the shade is made of glass, metal or other material according to the effect desired and has its 55 inner surface silvered or otherwise treated so as to act as a reflector. When the reflec-

tor is made of glass it is preferably continuous so as to make one piece with the diffuser proper.

Referring to the drawings, A is the diffuser; B is the shade; C the reflector; D are the frosted or translucent sides of the corrugations; E the sides that are clear or transparent; and F represents the arc filament or other source of light.

65

It will be observed that the slope or pitch of the corrugations is such, in reference to the position or positions of the source or sources of light, (which are arranged immediately above the middle longitudinal line 70 of the diffuser,) that only direct rays fall on the sides of the corrugations that are frosted, thus preventing the glare to the eyes when looking at or in the direction of the source of the light; while the reflected 75 or indirect rays (or most of them) will fall upon and pass relatively unhindered through those sides of the corrugations which are clear or transparent, thus furnishing a minimum of glare together with a maximum of 80 light.

5

The form of corrugation which is most effective (because offering the widest clear passage for reflected rays,) is that in which the sides of the corrugations which are 85 frosted are approximately vertical or at right angles to the general plane of the diffuser, as shown in Fig. 3 a and b.

It is of course understood that modifications may be resorted to, such as making the 90 corrugations latitudinal, diagonal, radial or even vertical, without departing materially from the scope or spirit of this invention, and such modifications are included herein.

Having thus described my invention, I 95 claim:

1. An oblong diffuser corrugated longitudinally and having the sides of the corrugations upon which the direct rays fall frosted so as to diffuse them, and the sides 100 upon which reflected rays fall, clear so as to permit them to pass without absorption, the said frosted sides being approximately perpendicular to the general plane of the diffuser so that the clear sides may be as wide 105 as possible, and said diffuser being backed by a reflector of corresponding size and shape and, together with the reflector, inclosing the source of light, which is so disposed with reference to the corrugations as 110 that no direct rays will pass through the clear sides thereof.

2. A combination of oblong diffusers corrugated longitudinally, and having the sides of the corrugations upon which direct rays fall frosted so as to diffuse them, and those upon which reflected rays fall, clear so as to pass them without absorption, the said diffusers being backed by reflectors of corresponding size and shape and, together with the reflectors, inclosing the sources of light, which are so disposed above the middle longitudinal lines of the diffusers as that no direct rays will fall upon the clear sides of their corrugations.

3. A combination of oblong diffusers corrugated longitudinally, and having the sides of the corrugations upon which direct rays fall frosted so as to diffuse them, and the

sides upon which reflected rays fall, clear so as to permit them to pass without absorption, the said frosted sides being approximately perpendicular to the general plane of the diffusers so that the clear sides may be as wide as possible, and the diffusers being backed by reflectors of corresponding size and shape and, together with said reflectors, inclosing the sources of light, which are so disposed with reference to the corrugations that no direct rays will fall upon the clear sides thereof. 20 25

In witness whereof I have hereunto set my hand at Chicago, Illinois, the 13th day of June, 1917. 30

ERNEST H. STRAUSS.
